UNITED STATES PATENT OFFICE.

CLARENCE B. ATWOOD, OF BELVIDERE, ILLINOIS, ASSIGNOR TO NATIONAL SEWING MACHINE COMPANY, OF BELVIDERE, ILLINOIS, A CORPORATION OF ILLINOIS.

TENSION DEVICE FOR SEWING-MACHINES.

1,129,945.

Specification of Letters Patent.

Patented Mar. 2, 1915.

Application filed January 31, 1912. Serial No. 674,448.

To all whom it may concern:

Be it known that I, CLARENCE B. Atwood, a citizen of the United States, residing at Belvidere, in the county of Boone and State 5 of Illinois, have invented certain new and useful Improvements in Tension Devices for Sewing-Machines, of which the following is a specification.

My invention relates to sewing machines, 10 and has more particular reference to improvements in mechanism for tensioning the thread to properly form the stitches.

Primarily the object of this invention is to provide improved means for insuring the 15 necessary tension upon the thread as it passes from the supply spool to the needle, which tensioning means will be extremely simple and reliable in construction, neat in appearance, and uniformly effective in operation.

A further object of my invention is to provide improved thread tension mechanism which will automatically accommodate itself to the different sizes of thread used, 25 and thereby maintain the proper sewing tension upon the thread throughout the range of sizes of thread which are used in sewing machines.

A further object of my invention is to provide improved tension mechanism which may be readily adjusted to operating conditions, and which, having been once set in that adjusted position, need not be disturbed during the operation of the machine.

A further object of my invention is to provide improved tension mechanism embodying means for properly tensioning the thread during the operation of the machine and means for entirely relieving the thread of 40 tension to permit the thread to be freely pulled when the cloth is removed from the machine.

A further object is to provide improved tension mechanism which will be practically "fool-proof" against being threaded wrongly, and which will be fully protected against damage or disturbance.

In order to attain these ends and accomplish other objects hereinafter appearing, 50 my invention consists in the features of novelty in the construction, combination and arrangements of parts herein claimed, described and shown in the accompanying

drawings which illustrate one embodiment of my invention, and in which—⁵⁵

Figure 1 is a face view of a sewing machine head embodying my invention. Fig. 2 is a similar view with the head plate or face plate removed to better show the internal parts of the head. Fig. 3 is a side elevation of that portion of the head sufficient to illustrate the application of my invention. Fig. 4 is a vertical sectional view of the irregular line 4—4 of Fig. 1. Fig. 5 is an enlarged central section of the main 60 thread tension device. Fig. 6 is a face view of the main thread tension device. Fig. 7 is an enlarged central sectional view of the auxiliary tension device on the line 7—7 of Fig. 1. Fig. 8 is an enlarged detail on line 70 8—8 of Fig. 7. Fig. 9 is a detail section on the line 9—9 of Fig. 7, and Fig. 10 is a perspective view of the tension release mechanism.

It will be readily apparent, after having obtained an understanding of my invention, 75 from the disclosures herein made, that my invention is applicable to various types of sewing machines, but for the purpose of an understanding of my invention, I have illustrated it as applied to a sewing machine head of well known construction.

Referring to the drawings, it will be seen that the sewing machine head 1 is of the hollow type, within which the operating mechanism is contained. A needle bar 2 having 85 a needle chuck 3 at its lower end, extends vertically through the head 1. This bar is reciprocated vertically by the crank and connecting rods 4 and 5 respectively, driven by 90 the shaft 6 shown in dotted lines in Fig. 2.

Parallel with the needle bar is a vertically movable presser foot bar 7, which carries at its lower end the usual presser foot 8 which, as is well known, coöperates with 95 other mechanism in the machine bed (not shown) to hold and feed the cloth in position while the stitches are being formed. This presser foot bar 7 has a long bore at its upper end which contains a spiral spring 100 9, the tension of which may be controlled and adjusted by means of a thumb screw 10 threaded into the upper portion of the head, the purpose of this arrangement, as is well known, being to cause the presser foot 105 to exert a yielding pressure upon the cloth

and feeding mechanism during the operation of the machine. A manually operated finger lever 11 is provided for raising and lowering the presser bar. In the structure 5 shown this lever projects into the interior of the head through a slot in the side wall thereof, and is pivoted at 12 to the wall of the head. The portion of this lever adjacent its pivot is formed as a cam 13, which 10 co-operates with the rearwardly turned lower end 14 of a multi-cam member 16 shown more clearly in Fig. 2. This multi-cam member 16 also has an upper rearwardly turned end 17 and both of the ends 15 are provided with holes 17' and 18' respectively through which the presser foot bar passes. The presser foot bar has a pin 19 which operates in an elongated slot 20 in the member 16, and in order to provide a 20 resilient lost motion connection between the presser foot bar and the member 16 a coiled spring is interposed between the pin 19 and the projection 17. The purpose of this arrangement is to relieve the presser foot bar 25 of all encumbrance, so that during the operation of the machine the presser foot frame rests upon the cloth and feeding mechanism under the sole action of the spring 9. The upper portion of the member 30 16 is disposed substantially horizontally in front of the needle bar and has long and short extensions 21 and 22 respectively. The long extension reaches to the upper portion of the head 1 and operates in a guiding 35 slot 23, as is clearly shown in Figs. 1 and 4. The upper end 24 of this extension is beveled to form a cam. The short extension 22 is beveled at its upper end and slightly curved rearwardly and also forms a cam.

40 In sewing machines of this character it is customary to provide a removable face or head plate 25, it being removably clamped in position by such means as a knurled head screw 26. This is for the purpose of permitting 45 access to the interior of the head to facilitate cleaning and adjusting the parts, repairing and oiling. In this structure I have illustrated the tension mechanism as mounted upon a removable plate of this 50 character, so that it may be removed therewith. The tension mechanism in this embodiment of my invention is divided into two parts, namely: the main tension device A and the auxiliary tension device B. The 55 thread C passes from the spool (not shown) over the top of the head and through the auxiliary tension device to the main tension device. From the main tension device it is threaded through the auxiliary slack take-up D, main slack take-up E, a guide F and thence to the needle 21.

60 In the particular structure shown the auxiliary tension device B is positioned adjacent the top of the head. At this point a short hollow tube or boss 27 is screwed

into the face of the plate and is covered at its outer end by a flat plate or head 27 (preferably circular), having a small central opening to admit the screw 28. This screw has a large (preferably circular and rounded) head or cap 29, which abuts against the smooth flat face of the head 27. The thread C passes downwardly between the two members 27 and 29, and in order that the thread may be properly guided and maintained in 75 place, I provide a narrow horizontal slot 30 in the member 27, as clearly shown in Fig. 9. The inner end of this slot is slightly enlarged, and the contiguous metal is smoothed off so as not to cut the thread. In the operation of sewing machines the tension upon the thread and the facility with which this tension may be controlled, play an important part in the proper formation of the 80 stitches. The fact is appreciated that the machine must accommodate a wide range in the size of thread, and since it would cause considerable annoyance and non-uniformity or results if the tension mechanism had to be adjusted for every size of thread, it is desirable that the tension mechanism automatically adapt itself to the various sizes of thread used. My improved tension mechanism is designed for this purpose. In the 85 face of the head or plate member 27 I provide a shallow slot or machine cut 31, so as to leave a space between the adjacent faces of the head 29 and the face of the member 27. This machine cut intersects the guide slot 30 so that the thread may pass through 90 the inner end of the guide slot and directly downwardly through the machine cut 31. These parts are preferably so proportioned that thread ranging in size down to about what is known as No. 60 may freely 95 pass through the cut. The coarser threads from about 60 down to what is known as No. 20, require more tension. In order that the tension mechanism may automatically accommodate the several sizes 100 of thread and apply the proper tension, I provide means which will cause the head 29 to exert a yielding pressure so that the coarser threads, being more or less larger in diameter than the depth of the cut or groove 105 31, will pass downwardly through the cut and force the head 29 outward. The proper degree of pressure will be exerted in accordance with the size of the particular thread used. In this structure the pressure is obtained by means of a coiled spring 33 which is interposed between a collar 32 on screw 28, and the head or member 27. The nut or collar 32 has a slot 34 in its face, by means of which it may be turned with a suitable 110 tool to regulate the pressure of the member 29 upon the thread. The end of the screw 28 is preferably split (see Fig. 8) to prevent the nut from working loose, and thereby 115 changing the adjustment. 120

125 130

It will be noted that the inner end of the screw 28 projects into the nut 23 in position to be actuated by the cam-end 24 of the extension 21 of member 16. Hence when the finger lever 11 is operated to raise the presser foot bar, the cam member 16 will also be raised. The cam 24 forces the screw 28 outwardly in counter-action to the spring 33, thus separating the members 27 and 29 and relieving the pressure of the member 29 upon the thread tension mechanism. The lowering or dropping of the presser foot again restores to action the tension mechanism without disturbing its adjustment.

The thread passes from the auxiliary tension mechanism to the main tension mechanism A, as shown in Fig. 1, and I have constructed this mechanism so that it will exert a uniform tension upon all sizes of thread used. The thread is preferably received on a rotary member such as a grooved pulley or wheel 40, around which the thread is given one turn. Outstanding from the face of the head plate 1 is a circular disk or member 41, having a depression 42 in its outer end or face. The depression or recess is larger in diameter than the tension pulley 40, and the pulley sets within this depression, as clearly shown in Fig. 5. The pulley is mounted upon a short centrally positioned stud 43, which projects through the disk member 41 and beyond the inner face of the plate 25. A forked leaf spring 44 is secured to the plate 25 and embraces the slotted inner end of the stud. This end of the stud 43 lies in the path of cam extension 22 of the member 16, and is so arranged that when, as before described, the presser foot bar and the member 16 are raised, the cam extension 22 will co-act with the end of the stud and force it outwardly against the tension of the spring 44. The outer end of the stud 43 is threaded internally and externally. It has a large rounded cap or head 45. This cap also has a depression 46 in its inner face, into which the other edge of the pulley sets. Between the pulley wheel 40 and the adjacent inner face of the cap 45 and the disk 41 I interpose friction washers 47, so that when the pulley wheel is clamped between these friction washers by the action of the spring 44, a yielding resistance is offered to the turning of the wheel, and tension will accordingly be applied to the thread. It will readily be seen that by turning the cap 45 upon the stud the degree of resistance offered to the wheel may be varied as desired. The adjusting of this tension mechanism is preferably performed at the factory before the machine is shipped, and in order to prevent the user of the machine from disturbing the adjustment, I split the end of the stud and provide a taper head screw 48 in the end of the stud. This expands the

end of the stud and locks the cap 46 firmly in its adjusted position. The raising of the presser foot bar, as heretofore described, forces the stud and cap or head 29 outwardly, as clearly shown in Fig. 5, and releases the wheel which may then be freely turned by the pull on the thread. As soon as the presser foot bar is lowered the parts are restored to normal position, but the adjustment is not in any way disturbed.

It will be noted that the tension mechanism is extremely simple, as the parts are so arranged, that it is practically impossible to thread the machine wrong. The outward surface of the main and auxiliary tension devices are perfectly smooth, and all sharp corners are avoided, hence these parts may be readily wiped and cleaned with a cloth without catching any of the ravelings and loose threads. Furthermore, the thread cannot enter the tension mechanism in any way except the right way. The tension pulley 40 is protected by the cap 45 and the disk member 41, the rims or edges of these members overhanging the pulley in such manner that it is practically impossible for the thread to get in behind the pulley and wind around the shaft. Furthermore, when the presser foot bar is raised, this being done at times when the cloth is shifted or removed from the machine, the thread is entirely relieved of the tension effect of the main and auxiliary tension devices, and the thread may be freely pulled through without any resistance to it. As soon as the presser foot bar again drops the same tension on the thread is again restored.

What I claim is:

1. In a thread tension mechanism for sewing machines, a main tension device and an auxiliary tension device comprising a stationary member having a depression in its face adapted to receive the thread, and a normally inactive member covering said depression and adapted to be brought into operation to effect a yielding pressure upon thread larger than a certain size.

2. In an automatic thread tension mechanism for sewing machines, a main tension device and an auxiliary tension device comprising two relatively separable members having a sufficient opening therebetween for admitting threads of certain sizes, and means for causing one of said members to exert a yielding pressure when threads of certain other sizes are passed through said opening.

3. In a thread tension mechanism for sewing machines, a main tension device and an auxiliary tension device comprising a stationary flat faced member having a recess extending across its face, in combination with a normally inactive pressure member disposed over said depression and a spring for said pressure member adapted to

be brought into action to cause pressure upon threads of certain sizes when said threads are passed through said recess.

4. In a thread tension device for sewing machines, a main tension device and an auxiliary tension device comprising a stationary member having a depression in its face in combination with a normally inactive pressure member covering said depression, and adapted to be brought into operation by threads of certain sizes when said threads are passed through said depression, and a guide slot communicating with said depression for guiding the thread thereinto.

5. The improvements herein described comprising a sewing machine head, in combination with a thread tension device mounted thereon and comprising a pair of tension clamps having an opening or thread slot therebetween through which threads of certain sizes may freely pass, said members being adapted to be rendered active to exert pressure upon threads of a different certain sizes when passed through said slot and a second tension device adapted to exert tension on threads of all sizes.

6. An automatic thread tension device for sewing machines, comprising a fixed member having a thread slot in its face, a normally inactive member normally covering said slot, spring mechanism for causing said member to exert a yielding pressure upon threads of certain sizes when passed through said slot, means for regulating the pressure of said member and means for exerting tension on threads of all sizes used with said tension device.

7. In a thread check for sewing machines, the combination with a fixed member and a normally inactive pressure member coöperating therewith, a space between said members admitting thread finer than a certain size, adjustable spring mechanism for causing the pressure member to exert a yielding pressure upon threads coarser than said certain size and additional tension means for exerting tension on threads finer than said certain size.

8. In an automatic thread check for sewing machines, the combination of a fixed hollow member having a grooved head, a pressure member normally abutting said head and disposed over said groove, said groove freely accommodating threads finer than a certain size, a spring arranged within said hollow member yieldingly holding said pressure member against said fixed member, whereby to exert pressure upon threads coarser than said certain size when passed through said groove and an additional tension device coöperating with threads used with said check.

9. The improvements herein described, comprising a sewing machine head, in combination with a member secured to and

projecting from said head and having a flat faced head, a thread groove in said flat face, a pressure member yieldingly held against the face of said projecting member, and adapted to automatically accommodate itself to threads of greater diameter than the depth of said groove and additional means for exerting tension on threads used with said device.

10. In a sewing machine, an operating head and a head plate secured thereto, in combination with a stud projecting from said plate, and having a flat member at its end, a guide slot in said flat member, a thread groove in the face of said member intersecting said slot, a thread tensioning device coöperating with and arranged to extend across said groove, and means for holding said tensioning device in yielding relation to a thread passing through said groove of larger diameter than the depth of the groove.

11. The improvements herein described, comprising a sewing machine head plate, in combination with a hollow stud mounted upon said plate, a grooved plate positioned at the end of said stud and having a guide slot intersecting the groove in said plate, a stem projecting through said hollow stud and having at its outer end a flat faced head abutting said grooved plate, a collar on said stem within said hollow stud, and a spring interposed between said collar and said grooved plate for causing said flat faced head to exert a yielding pressure upon threads of larger size than the depth of the groove in said grooved plate.

12. The improvements herein described, comprising a sewing machine head plate, in combination with a flat metal disk mounted upon said plate and having a thread groove in its face and a guide slot cut in its edge, said guide slot intersecting said groove and adapted to direct the thread into said groove, a pressure disk normally covering said groove, a stem carried by said pressure disk and extending through said flat disk, an adjustable collar on said stem, a coil spring surrounding said stem and constantly acting against said collar to hold said disks in contact and adapted to cause said pressure disk to exert a yielding pressure upon threads larger than the depth of said groove, and means whereby said collar may be turned to regulate the degree of pressure upon the thread.

13. In a device of the character described, a main tension member adapted to exert a substantially constant tension, and an auxiliary tension member adapted to exert tension on threads of certain sizes and to permit threads of certain other sizes to freely pass said auxiliary tension member.

14. In a device of the character described, a main tension member adapted to exert

tension on threads of all sizes used therewith, and an auxiliary tension member adapted to exert tension on threads of certain sizes and to permit threads of certain other sizes to freely pass said auxiliary tension member.

15. In a device of the class described, a main tension member adapted to exert a substantially constant tension, and an auxiliary tension member adapted to exert pressure on threads coarser than certain sizes

and to permit threads of finer sizes to freely pass said auxiliary tension member.

In testimony whereof I have signed my name to this specification, in the presence of 15 the subscribing witnesses, on this 22nd day of January A. D. 1912.

CLARENCE B. ATWOOD.
